UNITED STATES PATENT OFFICE.

EARL C. AKERS, OF PORT HURON, MICHIGAN.

DESIGN FOR A SHIP'S-LEVEL CASE.

SPECIFICATION forming part of Design No. 88,034, dated July 31, 1900.

Application filed June 6, 1900. Serial No. 18,330. Term of patent 14 years.

To all whom it may concern:

Be it known that I, EARL C. AKERS, a citizen of the United States, residing at Port Huron, in the county of St. Clair and State of Michigan, have invented and produced a certain new and original Design for a Ship's-
5 Level Case; and I do declare the following to be a full, clear, and exact description of the invention, such as will enable others skilled in
the art to which it appertains to make and use
10 the same.

The invention relates to a new and original design for a ship's-level case; and it consists of a design of the shape and configuration
15 shown in the accompanying drawings, in which—

Figure 1 is a front elevation of the case, and
Fig. 2 is an end view.

The leading features of the design consist in

the longitudinally-curved back A, the longitudinally-curved hollow front piece B, projecting therefrom and extending parallel therewith and provided with marginal ledges C, a longitudinally-curved vision-opening D, the apertured ears E at the end of the hollow front piece, and the apertured ear F, projecting upwardly from the central rear portion of the front piece. 20

What I claim is—

The design for a ship's-level case, as herein shown and described. 30

In testimony whereof I have hereunto set my hand in presence of two subscribing witnesses.

EARL C. AKERS.
